DIE BOX AND HOLDER

William H. Solger, Youngstown, Ohio, assignor to
 The Aetna Standard Engineering Company,
 Youngstown, Ohio, a corporation of Ohio

Application May 13, 1940, Serial No. 334,798

7 Claims. (Cl. 205—25)

This invention relates to wire drawing apparatus and more particularly to an improved die box and die holder and means for positioning and adjusting the die holder in the box.

5 In drawing wire it is usual to so dispose the axis of the die relative to the direction of movement of the wire therethrough that a cast or bend is imparted to the wire as it passes through the die. Different types of wire may require a 10 different angular position of the die to give the desired cast and in some instances it may be desired to impart more cast than at others.

It is, therefore, among the objects of my invention to provide an extremely simple and effective means for supporting a die holder in a die box whereby any desired degree of tilt may be imparted to the die and whereby the die is rigidly held in position during operation.

Other objects of my invention include: the provision of adjustable abutment means for taking the load imposed upon the die holder by the movement of the wire through the die, which means are readily adjustable and always provide a firm and even support for the die holder; the provision of means for varying the vertical position of the die holder which co-act with but are independent of the cast regulating mechanism; the provision of a die box which permits the die holder to be quickly and easily removed and replaced; and the provision of a simple, rugged, easily adjusted, economically manufactured die box and holder for wire drawing machines.

The above and other objects of my invention will appear from the following description of a preferred form thereof, reference being had to the accompanying drawing, in which—

Figure 1 is a plan view of our die box and holder assembly, a section of wire being illustrated extending through the die.

40 Figure 2 is an enlarged fragmentary vertical cross-sectional view taken on line 2—2 of Figure 1.

Figure 3 is an enlarged vertical cross-sectional view taken on line 3—3 of Figure 1.

45 Figure 4 is a fragmentary enlarged vertical cross-sectional view taken on line 4—4 of Figure 1.

Figure 5 is a fragmentary horizontal cross-sectional view taken on line 5—5 of Figure 3.

50 The die box is generally indicated at B and comprises an open topped, box-like structure having side walls 1 and 2, end walls 3 and 4 and floor 4a. In use the box is secured to the wire drawing machine in well known manner. The end wall 3 is formed with a bell mouthed aper-

ture 5 through which the wire 6 enters the portion of the box 7 which may be filled with a suitable lubricating material, such as tallow, soap or the like. The exit end 4 of the box is slotted at 8 to permit the wire to pass freely out of the 5 die box.

The die holder is generally indicated at H and may be of any suitable type. In the drawing a water cooled die holder is shown having a cooling water inlet 9 and outlet 10. It will be understood, however, that any suitable type of die holder may be employed. The die H, through which the wire is drawn, is suitably supported in the holder H, preferably with its axis perpendicular to the end face 12 of the holder. A fixed 10 flange 13 extends out from the end face 12 and is formed with a vertical cylindrical slot 14 therein. This slot 14 is open on one side, as seen in Figure 5, to permit the ball headed adjusting screw 15 to have limited universal movement 20 therein. The ball portion 15' of the screw 15 is disposed in the slot 14 and an adjustable die supporting screw 16 has threaded engagement with the cap 17 secured to the die box above the top of the slot 14. The screw 15 has threaded engagement with the end wall 4 and is disposed substantially midway between the top and bottom of the die box B.

The opposite side of the end face 12 of the die holder H from the flange 13 is formed with slide 30 surfaces 18 and 19 which support and guide the sliding flange 20. A removable plate 21, secured to the side of the die holder H by screws 22, is installed after the sliding flange 20 is placed in position and prevents the slide 20 from becoming detached from the die holder. A vertically extending cylindrical groove or slot 23, similar to slot 14, is formed in the sliding flange member 20 and the ball heads 24' and 25' of the screws 24 and 25 are disposed in the slot 23. These 40 two screws 24 and 25 are arranged in vertical alignment and have threaded engagement through the end wall 4 of the die box B. A die supporting screw 26 passes through the cap 27, which is secured to and movable with the slide 45 20, and rests upon the ball end 24' of the screw 24.

As is clearly seen in Figures 2 and 3, the screws 15, 24 and 25 are arranged in triangular relation. The weight of the die holder H is carried 50 by the screws 16 and 26 and a locking screw 28 is threaded through a cross bar 29 and abuts at its lower end against the top surface of the holder H. The bar 29 passes through yokes 30 and 31 on the sides of the box 20 and when the screw 55

28 is tightened down against the top of the die holder H the bar 29 will be pushed upwardly against the yokes 30 and 31 and the die holder H will be locked against upward movement in the box B.

5 By adjusting the screws 16 and 26 the vertical position of the die holder and die may be adjusted and by changing the positions of the three screws 15, 24 and 25 the axis of the die 10 H can be tilted to any desired degree in any direction. The screws 15, 24 and 25 are provided with socket heads, such as seen at 25" in Figure 4, to accommodate a suitable adjusting wrench.

15 As the position of the die holder is adjusted by the screws 15, 24 and 25 the sliding flange 20 may move transversely. It will be seen that, if the screw 15 remains in a given position, and the screws 24 and 25 are turned inwardly, a 20 swinging movement of the die holder about the ball head 15' will occur. This swinging movement is permitted by the sliding connection between the flange 20 and the body of the holder H.

25 My improved holder construction provides a three-point abutment for the die holder which forms at all times a firm, evenly distributed support for the die holder against the wire drawing force. The screw 28 prevents any jumping or 30 vibrating of the holder during operation and the open bottomed cylindrical slots 14 and 23 permit the die holder to be removed from the die box simply by removing the screw 28 and bar 29 and then lifting the box vertically to disengage it 35 from the ball ends of the screws 15, 24 and 25.

My improved die box and holder construction permits easy and accurate adjustment of the position of the axis of the die to give the desired cast to the wire. In any adjusted position 40 a firm abutment for the die is automatically obtained against the box end 4 and this firm abutment is automatically obtained due to the three-point engagement of the holder H with the ball ends of the screws 15, 24 and 25. With my 45 apparatus die holders can be easily and quickly changed without changing the cast of the wire and any necessary adjustments can readily be made.

Although I have described the illustrated embodiment of my invention in considerable detail 50 it will be understood that variations and modifications in the form of the apparatus employed may be made without departing from the spirit of my invention. I do not, therefore, wish to be limited to the particular apparatus shown and described but claim as my invention all forms 55 thereof coming within the scope of the appended claims.

I claim:

60 1. In wire drawing apparatus, a die box and a die holder and means for positioning said holder in said box including walls defining a fixed slot at one end of said holder, a slid able member carried by said holder and having a slot parallel to said fixed slot and movable with said slid able member toward and away from said fixed slot, a single adjustable abutment member carried by said box and having a head disposed in one of said slots, and two adjustable abutment members carried by said box and having heads disposed in the other slot whereby triangularly arranged abutments are provided between said 65 holder and said box.

70 2. Wire drawing apparatus including, a die 75 box having a floor and an end wall, a die holder

adapted to be disposed in said die box, said die holder having a vertical slot at one end, said slot being disposed on one side of the die axis, a movable flange mounted on said holder for horizontal sliding movement relative thereto, said movable flange having a slot extending parallel to said first named slot and on the opposite side of said die axis therefrom, a single adjusting screw extending through said box end wall and having a head portion disposed in one of said slots, a pair of adjusting screws extending through said end wall and having head portions disposed in the other of said slots, and adjustable support means carried by said die holder for supporting same on said single screw and one of 15 said pair of screws.

3. Wire drawing apparatus including, a die box having a floor and an end wall, a die holder adapted to be disposed in said die box, said die holder having a vertical slot at one end, said slot being disposed on one side of the die axis, a movable flange mounted on said holder for horizontal sliding movement relative thereto, said movable flange having a slot extending parallel to 20 said first named slot and on the opposite side of said die axis therefrom, a single adjusting screw extending through said box end wall and having a head portion disposed in one of said slots, a pair of adjusting screws extending through said end wall and having head portions 25 disposed in the other of said slots, adjustable support means carried by said die holder for supporting same on said single screw and one of said pair of screws, and releasable means coacting with said die box for holding said die holder down with said support means in engagement with said screws.

4. In apparatus of the class described, a die box having an end wall having an aperture through which wire being drawn may pass, three 40 ball headed adjusting screws threaded through said end wall, one of said screws being on one side of the center of said aperture and the other two screws being on the other side of said center, and a die holder in said box having parallel slots 45 at one end thereof, said slots being of circular cross-sectional form and adapted to fit over the ball heads of said screws, the ball head of one of said screws being disposed in one of said slots and the ball head of each of the other two screws 50 being disposed in the other slot.

5. In apparatus of the class described, a die box having an end wall having an aperture through which wire being drawn may pass, three ball headed adjusting screws threaded through 55 said end wall, one of said screws being on one side of the center of said aperture and the other two screws being on the other side of said center, a die holder in said box having parallel slots at one end thereof, said slots being of circular cross-sectional form and adapted to fit over the ball heads of said screws, the ball head of one of said screws being disposed in one of said slots and the ball head of each of the other two screws 60 being disposed in the other slot, and adjustable means for supporting said die holder on said screws.

6. In apparatus of the class described, a die box having an end wall having an aperture through which wire being drawn may pass, three 70 ball headed adjusting screws threaded through said end wall, one of said screws being on one side of the center of said aperture and the other two screws being on the other side of said center, a die holder in said box having parallel slots at 75

- one end thereof, said slots being of circular cross-sectional form and adapted to fit over the ball heads of said screws, the ball head of one of said screws being disposed in one of said slots and 5 the ball head of each of the other two screws being disposed in the other slot, adjustable means for supporting said die holder on said screws, and means for clamping said holder in position in said box.
- 10 7. In apparatus of the class described, a die box having an end wall having an aperture through which wire being drawn may pass, three ball headed adjusting screws threaded through said end wall, one of said screws being on one 15 side of the center of said aperture and the other
- two screws being on the other side of said center, a die holder in said box having parallel slots at one end thereof, said slots being of circular cross-sectional form and adapted to fit over the ball heads of said screws, the ball head of one of said screws being disposed in one of said slots and the ball head of each of the other two screws being disposed in the other slot, adjustable means for supporting said die holder on said screws, means for clamping said holder in position in 10 said box, and means for permitting sliding movement of one of said slots toward or away from the other slot.
